(57) **ABSTRACT**

An icemaker appliance is provided, the appliance including a conduit fluidly coupling together a water reservoir, an icemaking vessel, and an ice reservoir. The appliance includes a pump configured to flow water through the conduit. The icemaking vessel includes an auger positioned at least partially within a cylinder. A flowpath is formed between the cylinder and the auger. The auger forms an auger conduit extending in fluid communication from the flowpath to an outlet opening outside of the flowpath.

**ICEMAKER APPLIANCE AND METHOD
FOR OPERATION TO PREVENT FROZEN
AUGER**

**CROSS-REFERENCE TO RELATED
APPLICATIONS**

The present application is the National Stage Entry of and claims the benefit of priority under 35 U.S.C. § 371 to PCT Application Serial No. PCT/CN2022/133094 filed Nov. 21, 2022, and entitled ICEMAKER APPLIANCE AND METHOD FOR OPERATION TO PREVENT FROZEN AUGER which is hereby incorporated by reference in its entirety.

FIELD

The present subject matter relates generally to freezer appliances, and more particularly to icemaker appliances and methods for operation to prevent auger seizure.

BACKGROUND

Icemaking appliances use water to generate ice or nugget ice. Water will generally include minerals that build up at various components and pathways of the icemaker appliance, such as at a bottom of an icemaking cylinder. As minerals builds up at components and pathways the icemaker appliance, levels of total dissolved solids (TDS) increase. Increasing TDS levels at water can decrease the freezing point of water, which inhibits and prevents generation of ice. To remove mineral build-up, a user may need to manually access various components of the icemaker appliance and clear away the mineral build-up. Such manual removal may be difficult for a user to access all of the necessary components and pathways. Still further, manually cleaning such components and pathways may introduce a risk of a user damaging surfaces or components when clearing away mineral build-up.

Icemaker appliances generally include icemaking chambers that generate ice. Over time, ice builds up at the icemaking chamber, which adversely affects pressure at the icemaking chamber, such as by causing water levels to decrease. The effect of decreasing water levels may allow for ice build-up to continue, may cause ice to form and stay within the icemaking chamber, or otherwise cause an icemaking auger to seize in place and be inhibited from rotation.

Accordingly, structures and methods for removing ice build-up at icemaking chambers are desired and would be advantageous. Furthermore, structures and methods for removing mineral build-up and reducing TDS at icemaker appliances are desired and would be advantageous.

BRIEF DESCRIPTION

Aspects and advantages of the invention will be set forth in part in the following description, or may be obvious from the description, or may be learned through practice of the invention.

An aspect of the present disclosure is directed to an icemaker appliance. The appliance includes a conduit fluidly coupling together a water reservoir, an icemaking vessel, and an ice reservoir. The appliance includes a pump configured to flow water through the conduit. The icemaking vessel includes an auger positioned at least partially within a cylinder. A flowpath is formed between the cylinder and

the auger. The auger forms an auger conduit extending in fluid communication from the flowpath to an outlet opening outside of the flowpath.

These and other features, aspects and advantages of the present invention will become better understood with reference to the following description and appended claims. The accompanying drawings, which are incorporated in and constitute a part of this specification, illustrate embodiments of the invention and, together with the description, serve to explain the principles of the invention.

BRIEF DESCRIPTION OF THE DRAWINGS

A full and enabling disclosure of the present invention, 15 including the best mode thereof, directed to one of ordinary skill in the art, is set forth in the specification, which makes reference to the appended figures.

FIG. 1 provides a front view of an icemaker appliance in accordance with aspects of the present disclosure;

20 FIG. 2 provides a cutaway internal view of an embodiment of an icemaker appliance in accordance with aspects of the present disclosure;

FIG. 3 provides a schematic flow diagram of an icemaker appliance in accordance with aspects of the present disclosure;

25 FIG. 4 provides a schematic flow diagram of an icemaker appliance in accordance with aspects of the present disclosure;

FIG. 5A provides a schematic side view of an icemaking 30 vessel of the icemaker appliance in accordance with aspects of the present disclosure;

FIG. 5B provides a schematic side view of an icemaking vessel of the icemaker appliance in accordance with aspects of the present disclosure; and

35 FIG. 6 provides a schematic flowchart of method for operating an icemaker appliance in accordance with aspects of the present disclosure.

DETAILED DESCRIPTION

Reference now will be made in detail to embodiments of the invention, one or more examples of which are illustrated in the drawings. Each example is provided by way of explanation of the invention, not limitation of the invention.

45 In fact, it will be apparent to those skilled in the art that various modifications and variations can be made in the present invention without departing from the scope or spirit of the invention. For instance, features illustrated or described as part of one embodiment can be used with another embodiment to yield a still further embodiment. Thus, it is intended that the present invention covers such modifications and variations as come within the scope of the appended claims and their equivalents.

As used herein, the terms "first," "second," and "third" 50 may be used interchangeably to distinguish one component from another and are not intended to signify location or importance of the individual components. The terms "includes" and "including" are intended to be inclusive in a manner similar to the term "comprising." Similarly, the term "or" is generally intended to be inclusive (i.e., "A or B" is 55 intended to mean "A or B or both"). In addition, here and throughout the specification and claims, range limitations may be combined or interchanged. Such ranges are identified and include all the sub-ranges contained therein unless 60 context or language indicates otherwise. For example, all ranges disclosed herein are inclusive of the endpoints, and the endpoints are independently combinable with each other.

The singular forms "a," "an," and "the" include plural references unless the context clearly dictates otherwise.

Approximating language, as used herein throughout the specification and claims, may be applied to modify any quantitative representation that could permissibly vary without resulting in a change in the basic function to which it is related. Accordingly, a value modified by a term or terms, such as "generally," "about," "approximately," and "substantially," are not to be limited to the precise value specified. In at least some instances, the approximating language may correspond to the precision of an instrument for measuring the value, or the precision of the methods or machines for constructing or manufacturing the components or systems. For example, the approximating language may refer to being within a 10 percent margin (i.e., including values within ten percent greater or less than the stated value). In this regard, for example, when used in the context of an angle or direction, such terms include within ten degrees greater or less than the stated angle or direction (e.g., "generally vertical" includes forming an angle of up to ten degrees in any direction, such as, clockwise or counterclockwise, with the vertical direction V).

Embodiments are provided herein of an icemaker appliance **100** and methods for operation **1000** for removing mineral build-up and reducing total dissolved solids (TDS) of water at icemaker appliances are provided. Structures and methods provided herein include reservoirs, conduits, and control instructions for performing a cleaning cycle that includes operating a water pump and ice maker auger, flowing water through an icemaking cylinder to mix the flowing water between a first (e.g., upper) reservoir and a second (e.g., lower) reservoir to dilute the water at the first reservoir and provide low TDS water to the second reservoir.

Referring now to the drawings, FIG. 1 provides a front view of an embodiment of an icemaker appliance **100** in accordance with aspects of the present disclosure. Icemaker appliance **100** forms an icemaking freezer appliance configured to receive a supply of water to generate ice or nugget ice. In particular embodiments, icemaker appliance **100** forms a nugget icemaker appliance. In various embodiments, appliance **100** includes an ice reservoir **160** at which ice, such as nugget ice **14**, is provided and retained. In certain embodiments, a water reservoir **20** is positioned in fluid communication such as to provide water for making ice **14** and providing ice to ice reservoir **160**, such as described below.

Referring now to FIG. 2, a cutaway perspective view of an embodiment of the icemaker appliance **100** is provided. Appliance **100** includes an interior **12** formed by cabinet at which various components and conduits forming pathways are disposed. Appliance **100** includes a first reservoir **110** forming an upper reservoir relative to a second reservoir **120** forming a lower reservoir. Each reservoir **110, 120** is configured to receive quantities of water and flow the water to an icemaking cylinder **130**. Appliance **100** includes a heat exchanger system, such as including a compressor (not shown) configured to flow and provide a refrigerant in thermal communication to cylinder **130**, or additionally, auger **140**, to remove heat from the cylinder **130** such that water provided to the cylinder **130** freezes and generates ice. Auger **140** is positioned within cylinder **130** and is operably coupled to a motor or other drive device to rotate along a central vertical axis. Rotation of auger **140** scrapes ice from the cylinder **130** and pushes the ice upward to an exit chute **150**. A shaping device **142**, such as a cone, is positioned to break the ice egressing from the cylinder **130** and auger **140**.

toward the chute **150**. Ice, or particularly nugget ice, egresses the cylinder **130** via chute **150** and is provided to an ice reservoir **160**.

Referring now to FIGS. 2-4, in various embodiments, appliance **100** includes a plurality of conduits fluidly coupled to flow water from the second reservoir **120** to the first reservoir **110** via conduit **122**. FIGS. 3-4 provide schematic depictions of flow of water through appliance **100** in accordance with embodiments of the present disclosure.

5 Pump **170**, operably coupled to motor **172**, flows water from second reservoir **120** through conduit **122** to conduit **124** to first reservoir **110**. Water is allowed to drain from first reservoir **110** into drain conduit **126** through opening **125** at first reservoir **110**. A drain plug **127** is positioned at a downstream end of drain conduit **126** and may be desirably articulated to release and drain water from drain conduit **126** or retained at drain conduit **126**.

Fluidly between drain plug **127** and opening **125** at first reservoir **110** is a supply conduit **132** extending in fluid communication from drain conduit **126** to cylinder **130**. In various embodiments, supply conduit **132** is configured to provide water to a bottom end of cylinder **130**, or particularly to a flowpath **135** (FIGS. 5A-5B). When the heat exchanger system is in operation to freeze the cylinder **130**, water flowed to cylinder **130** is frozen and ice is generated, such as described above. In other methods for operation, such as further described herein, the heat exchanger system is disengaged or not operating such that cylinder **130** is above freezing temperature. Accordingly, water is allowed to flow through cylinder **130** and in fluid communication with auger **140**. Water is furthermore allowed to build-up and flow through an exit **134** of cylinder **130** (e.g., a top or upper exit) and along chute **150** and into ice reservoir **160**. Water received and built-up at ice reservoir **160** is allowed to flow and egress from an opening **162** from ice reservoir **160** into second reservoir **120**. In certain embodiments, ice reservoir **160** is positioned above second reservoir **120**, such as to allow gravity to flow water from ice reservoir **160** through opening **162** into second reservoir **120**. Water may further flow from second reservoir **120** through an opening **164** to conduit **122**. Accordingly, a substantially closed-loop circuit may be formed allowing water to flow from second reservoir **120** through first reservoir **110**, cylinder **130**, auger **140**, chute **150**, and ice reservoir **160**.

45 In certain embodiments, appliance **100** includes water supply conduit **121** extending from a water source to second reservoir **120**, such as via opening **166**. However, it should be appreciated that in various embodiments water may be manually provided by a user (e.g., into water reservoir **20** in FIG. 1), or provided at other portions or components of the closed-loop circuit such as described herein.

50 Referring back to FIG. 1, operation of appliance **100** is regulated by a control device or controller **200** that is operatively coupled to user interface panel **220**. Controller **200** may include one or more processors **210** and one or more memory devices **212**. The one or more memory devices **212** may be configured to store instructions **214** that, when executed by the one or more processors **210**, causes the appliance **100** to perform operations, such as one or more steps of methods for operation **1000** further provided herein. The memory device(s) **212** may be configured to store instructions **214**, or related steps, data, schedules, etc. for operating appliance **100** in accordance with method **1000**.

55 Panel **220** provides selections for user manipulation of the operation of appliance **100** such as e.g., selections between a cleaning mode provided by method **1000** and an icemaking operation. In response to user manipulation of the user

interface panel 220, the controller 200 operates various components of the appliance 100. Controller 200 may be positioned in a variety of locations throughout appliance 100. In the illustrated embodiment shown in FIG. 1, the controller 200 is located within or behind the user interface panel 220 at cabinet 10. In such an embodiment, input/output ("I/O") signals may be routed between controller 200 and various operational components of appliance 100. In one exemplary embodiment, the user interface panel 220 may represent a general purpose I/O ("GPIO") device or functional block. In another exemplary embodiment, the user interface 220 may include input components, such as one or more of a variety of electrical, mechanical, or electro-mechanical input devices including push buttons, touch pads, touch screens, etc.

The user interface 220 may be in communication with a communications device 216 at controller 200, such as via one or more wired or wireless signal lines or shared communication busses. Communications device 216 may include any appropriate wired or wireless interface. Communications device 216 may furthermore be configured to communicate with a remote device, such as, but not limited to, a smartphone, tablet, computing device, or interconnected device, or network computing apparatus. Accordingly, one or more steps of method 1000 may be stored, transmitted, or executed from the remote device. Still further, operation signals, such as one or more signals indicative of present, past, or upcoming operation of appliance 100 in a cleaning mode, an icemaking mode, or other operating mode, may be provided to the user interface 220, the remote device, or both.

Referring now to FIGS. 5A-5B, a schematic side view of exemplary embodiments of an icemaking vessel 128 of the appliance 100 are provided. Icemaking vessel 128 includes auger 140 positioned within cylinder 130. Auger 140 includes a rotatable shaft 141 having a cutting tool or blade 143 positioned at the rotatable shaft 141. Auger 140 positioned within cylinder 130 forms a flowpath 135 between auger 140 and cylinder 130. Icemaking vessel 128 is positioned at least partially within a housing. Housing may include upper housing 16 at least partially surrounding an upper portion 137 of cylinder 130, such as proximate to exit 134.

In certain embodiments, shaft 141 includes an upper portion 1411 extending through upper housing 16. Upper housing 16 is configured to retain shaft 141. In particular embodiments, shaft 141 is extended vertically through upper housing 16. Upper housing 16 may include any appropriate seals, bearings, or other components allowing for rotation of shaft 141. In still particular embodiments, upper portion 1411 of shaft 141 extends through upper housing 16.

Referring still to FIGS. 5A-5B, the housing of the icemaking vessel 128 may include lower housing 18 forming a seal at auger 140 and cylinder 130. Lower housing 18 may include any appropriate seals, bearings, or other components allowing for rotation of shaft 141. In particular embodiments, shaft 141 includes a lower portion 1142 extending through lower housing 18. Lower housing 18 forming a seal at cylinder 130 and auger 140 fluidly seals water at flowpath 135.

Auger 130 forms a conduit 131, such as a central bore, or one or more bores, extending in fluid communication from flowpath 135 and above a maximum water level or height 145 of water at flowpath 135, such as substantially corresponding to a vertical height of exit 134 to chute 150. Auger 130 forms an opening 133 allowing fluid communication from flowpath 135 to conduit 131. In various embodiments,

opening 133 is formed along a vertically extending sidewall 1413 of shaft 141. In still various embodiments, opening 133 is formed at any location along a vertical direction at auger 130. In particular embodiments, such as depicted in FIG. 5A, opening 133 is formed proximate to a lower end 139 of flowpath 135 distal along a vertical direction to the exit 134 or upper portion 137. In other embodiments, such as depicted in FIG. 5B, opening 133 is formed proximate to exit 134 of flowpath 135 and distal along a vertical direction to lower end 139.

In various embodiments, conduit 131 is formed through shaft 141 extending substantially vertically from opening 133. In particular embodiments, auger 140 forms an outlet opening 136 at conduit 131 distal along the vertical direction from the opening 133 (e.g., inlet opening). In still particular embodiments, opening 136 is positioned above the maximum water level or height 145 of water at flowpath 135. In certain embodiments, opening 136 is positioned above the upper housing 16 along the vertical direction.

Auger 140 may include shaft 141 formed as an integral, monolithic component, such as formed via casting, machining from a unitary material, additively manufactured, or combinations thereof. However, in other embodiments, shaft 141 may be formed of several components joined together, such as, but not limited to, via mechanical fasteners, adhesives, welding, brazing, etc. Conduit 131 may extend vertically through upper portion 1141 and a main shaft body 1414 (e.g., portion positioned between upper portion 1411 and lower portion 1412). Conduit 131 may extend from opening 133 and terminate at opening 136, such as to direct fluid flow from opening 133 to opening 136. Conduit 131 is formed substantially along the vertical direction and may further include perpendicular or oblique extensions, such as from a vertical extension to the sidewall 1413 of shaft 141 at which opening 133 is formed.

During operation of appliance 100, water level 145 at icemaking vessel 128 is substantially equal to first reservoir 110 (FIGS. 2-3). Exit opening 134, or openings at upper housing 16, may allow flowpath 135 to vent with air external to the icemaking vessel, such as to allow water level 145 to be substantially equal between icemaking vessel 128 and first reservoir 110. Exit opening 134, or openings at upper housing 16, may form an opening to atmospheric pressure. Conduit 131 at auger 140 may mitigate blockage or build-up of ice at flowpath 135, at exit opening 134, or an area proximate to upper portion 137 of cylinder 130 generally. Conduit 131 provides a vent opening, such as from opening 133 to opening 136, allowing inside of cylinder 130, or particularly flowpath 135 to exit opening 134, to vent (e.g., to atmospheric pressure) and generate an air pressure balance. The air pressure balance allows for water levels 145 at icemaking vessel 128 and first reservoir 110 to remain substantially equal, allowing for rotation of auger 140 and mitigating ice build-up that may otherwise inhibit rotation of auger 140.

Referring now to FIG. 6, a schematic flowchart outlining steps of a method for operating an ice maker appliance ("method 1000") is provided. Embodiments of method 1000 provide a cleaning mode or operation for removing minerals and reducing total dissolved solids (TDS) at an icemaking appliance. Embodiments of method 1000 may be stored as steps or instructions at a controller or network computing device and executed at a freezer appliance or an icemaker appliance, such as controller 200 and appliance 100 depicted and described herein. However, it should be appreciated that various embodiments of method 1000 may be stored, performed, and executed at various other embodiments of

icemaking appliances. Particular embodiments of method 1000 may be executed at a standalone icemaking appliance, such as an icemaker appliance separate from a refrigerator appliance, or an icemaker appliance separate from a freezer appliance.

Method 1000 includes at 1010 discontinuing operation of a heat exchanger system, such as to allow a temperature at an icemaking vessel (e.g., icemaking vessel 128, cylinder 130, auger 140) to be above freezing temperature of water.

Method 1000 includes at 1020 flowing water in a closed loop circuit between the icemaking vessel, an ice reservoir, and a water reservoir (e.g., first reservoir 110). In certain embodiments, flowing water in closed loop circuit includes building a water height at the water reservoir to approximately an equal level to a height of the icemaking vessel. In particular embodiments, flowing water in the closed loop circuit includes flowing water through the closed loop circuit for a plurality of cycles. In still particular embodiments, method 1000 includes egressing water from the icemaking vessel to the ice reservoir via an upper exit at the icemaking vessel. In certain embodiments, the upper exit is positioned at an approximately equal height to the height of the icemaking vessel (e.g., water level 145 in FIGS. 5A-5B). Accordingly, all, or substantially all, of a volume of the icemaking vessel is flowed with water during, or as a result of, step 1020.

In certain embodiments, the closed loop circuit includes a lower reservoir (e.g., reservoir 120) relative to an upper reservoir (e.g., reservoir 110). Upper reservoir is positioned substantially equal in height to the icemaking vessel (e.g., cylinder 130). In particular, upper reservoir is positioned to allow a substantially equal water level or height (e.g., water level 145) at the icemaking vessel and the upper reservoir. The closed loop circuit may further include fluid communication with an auger (e.g., auger 140) at the icemaking vessel. Certain embodiments further include the closed loop circuit in fluid communication with a conduit (e.g., conduit 131) and flowpath (e.g., flowpath 135) at the icemaking vessel. Still particular embodiments include the closed loop circuit at an ice egress chute (e.g., chute 150) and into an ice reservoir (e.g., ice reservoir 160) and back into lower reservoir.

Method 1000 may particularly include at 1030 operating a pump (e.g., pump 170) to flow water through the closed loop circuit. Still particular embodiments include discontinuing operation of the heat exchanger system to allow for the temperature at the icemaking vessel to rise above freezing temperature of water, then operating the pump to flow water through the closed loop circuit.

In certain embodiments, a user may manually remove ice from the ice reservoir and provide inputs at user interface 220 to command performance of method 1000. Accordingly, method 1000 may be performed for a first period of time until mineral build-up at the icemaking vessel, auger, or various reservoirs may be removed or substantially decreased. Following one or more iterations of step 1020, method 1000 may include at 1040 draining the water (e.g., via drain conduit 126 and drain plug 127). In particular embodiments, step 1040 includes draining the water through a drain plug after completing a plurality of cycles of flowing water though the closed loop circuit.

In still certain embodiments, method 1000 may be performed for a plurality of cycles of step 1020 for a second period of time until ice that may be present at ice reservoir 65 may be melted and removed. For instance, method 1000 may be performed at a predetermined time (e.g., night-time,

daytime working hours, weekly, monthly, or user-determined time, etc.) without regard for presence of ice at the ice reservoir.

In still yet various embodiments, method 1000 includes at 1050 restarting operation of the heat exchanger system. Method 1000 at 1050 allows temperature at the icemaking vessel to decrease to, or below, the freezing temperature of water, such as to allow for generation of ice. In particular embodiments, step 1010 shuts down the components or subsystems configured to remove heat and freeze the water, such as the heat exchanger system. Step 1020 is performed following restart of the appliance, such as prior to operating the heat exchanger system to remove heat and freeze water to generate ice and provide ice to the ice reservoir.

Particular embodiments of method 1000 and appliance 100 provided herein may be particular to nugget icemaking appliances. Nugget icemaking appliances may contrast with other icemaking devices (e.g., refrigerator appliances), such as by an absence of trays of water configured to retain water until ice is frozen, or by including moving or rotary components at nugget icemaking appliances (e.g., auger 140 within cylinder 130) configured to generate ice while moving the ice through a flowpath (e.g., flowpath 135), or the relative speed of a nugget ice maker in generating ice in contrast to refrigerator appliances. One skilled in the art will appreciate that such differences in structure and operation may patentably separate nugget icemaking appliances from other icemaking devices. Furthermore, appliances, such as appliance 100 and method 1000 provided herein, may allow for icemaking and cleaning operation not allowed by other icemaking devices.

Further aspects of the present disclosure are provided in one or more of the following clauses:

1. An icemaker appliance, including a closed loop circuit including a conduit fluidly coupling together a water reservoir, an icemaking vessel, and an ice reservoir; a pump configured to flow water through the conduit; and a controller configured to selectively operate the pump and the icemaking vessel, the controller configured to allow a temperature at the icemaking vessel to be above freezing temperature of water at the conduit; and operate the pump to flow water through the closed loop circuit.
2. The icemaker appliance of any one or more of the clauses herein, the controller configured to operate the pump to flow water through the closed loop circuit after the temperature at the icemaking vessel is above freezing temperature of water at the conduit.
3. The icemaker appliance of any one or more of the clauses herein, the controller configured to operate the pump to flow water through the closed loop circuit for a plurality of cycles through the closed loop circuit.
4. The icemaker appliance of any one or more of the clauses herein, the controller configured to operate the pump to flow water through the closed loop circuit for a plurality of cycles through the closed loop circuit until ice at the ice reservoir is removed.
5. The icemaker appliance of any one or more of the clauses herein, the controller configured to drain the water through a drain plug after completing a plurality of cycles of flowing water though the closed loop circuit.
6. The icemaker appliance of any one or more of the clauses herein, the controller configured to build a water height at the water reservoir to approximately an equal level to a height of the icemaking vessel.

7. The icemaker appliance of any one or more of the clauses herein, the controller configured to egress water from the icemaking vessel to the ice reservoir via an upper exit at the icemaking vessel, the upper exit at an approximately equal height to the height of the ice-making vessel. 5
8. The icemaker appliance of any one or more of the clauses herein, wherein the icemaker appliance is a nugget icemaking appliance.
9. The icemaker appliance of any one or more of the clauses herein, the controller configured to allow a temperature at the icemaking vessel to be above freezing temperature of water at the conduit, and to operate the pump to flow water through the closed loop circuit for a first period of time until mineral build-up at the icemaking vessel is decreased. 10
10. The icemaker appliance of any one or more of the clauses herein, the controller configured to allow a temperature at the icemaking vessel to be above freezing temperature of water at the conduit, and to operate the pump to flow water through the closed loop circuit following restart of the icemaker appliance. 15
11. The icemaker appliance of any one or more of the clauses herein, the controller configured to discontinue operation of a heat exchanger system to allow a temperature at the icemaking vessel to be above freezing temperature of water at the conduit. 20
12. The icemaker appliance of any one or more of the clauses herein, the controller configured to drain the water through a drain plug after completing a plurality of cycles of flowing water though the closed loop circuit; then restart operation of the heat exchanger system. 25
13. A computer-implemented method for reducing total dissolved solids at an icemaking appliance, the icemaking appliance including a closed loop circuit including a conduit fluidly coupling together a water reservoir, an icemaking vessel, and an ice reservoir, the icemaking appliance including a pump configured to flow water through the conduit, and a heat exchanger system configured to selectively operate to remove heat from the icemaking appliance to generate ice, the method including discontinuing operation of the heat exchanger system to allow a temperature at the ice-making vessel to be above freezing temperature of water at the conduit; operating the pump to flow water through the closed loop circuit. 30
14. The method of any one or more of the clauses herein 35
- 13, the method including draining the water after completing a plurality of cycles of flowing water though the closed loop circuit; then restarting operation of the heat exchanger system to remove heat from the icemaking appliance to generate ice.
15. The method of any one or more of the clauses herein, wherein operating the pump to flow water through the closed loop circuit is after the temperature at the icemaking vessel is above freezing temperature of water at the conduit. 50
16. The method of any one or more of the clauses herein, 60
- the method including waiting, for a predetermined period of time, after discontinuing operation of the heat exchanger system, wherein the predetermined period of time corresponds to a period of time for water at the icemaking vessel to be above freezing temperature of water, then operating the pump to flow water through the closed loop circuit. 65

17. The method of any one or more of the clauses herein, wherein operating the pump includes operating the pump to flow water through the closed loop circuit for a plurality of cycles through the closed loop circuit.
18. The method of any one or more of the clauses herein, wherein operating the pump includes operating the pump to flow water through the closed loop circuit for a plurality of cycles through the closed loop circuit until ice at the ice reservoir is removed.
19. The method of any one or more of the clauses herein, wherein operating the pump includes building a water height at the water reservoir to approximately an equal level to a height of the icemaking vessel.
20. The method of any one or more of the clauses herein, wherein operating the pump includes egressing water from the icemaking vessel to the ice reservoir via an upper exit at the icemaking vessel, the upper exit at an approximately equal height to the height of the ice-making vessel.
21. An icemaker appliance including a conduit fluidly coupling together a water reservoir, an icemaking vessel, and an ice reservoir; and a pump configured to flow water through the conduit, wherein the icemaking vessel includes an auger positioned at least partially within a cylinder, wherein a flowpath is formed between the cylinder and the auger, the auger forming an auger conduit extending in fluid communication from the flowpath to an outlet opening outside of the flowpath. 25
22. The icemaker appliance of any one or more clauses herein, wherein the auger includes a shaft, the shaft forming a sidewall at which an inlet opening of the auger conduit is formed.
23. The icemaker appliance of any one or more clauses herein, wherein the icemaking vessel forms an exit opening to the ice reservoir, an atmospheric pressure, or both, and wherein the auger forms an outlet opening at the auger conduit, the outlet opening positioned above the exit opening. 30
24. The icemaker appliance of any one or more clauses herein, wherein the inlet opening is positioned in fluid communication with the flowpath.
25. The icemaker appliance of any one or more clauses herein, wherein the conduit is formed in fluid communication with the flowpath at the icemaking vessel.
26. The icemaker appliance of any one or more clauses herein, wherein the conduit is formed in fluid communication with the auger conduit.
27. The icemaker appliance of any one or more clauses herein, wherein the icemaking vessel includes an upper housing and a lower housing, and wherein the auger includes a shaft, the shaft forming an upper portion extending through the upper housing, the shaft forming a lower portion extending through the lower housing. 40
28. The icemaker appliance of any one or more clauses herein, wherein the auger conduit is formed extending substantially vertically through a main shaft body formed between the upper portion and the lower portion.
29. The icemaker appliance of any one or more clauses herein, wherein the auger conduit extends through the upper portion, and wherein the outlet opening is positioned at the upper portion.
30. The icemaker appliance of any one or more clauses herein, wherein the outlet opening is positioned at the upper portion of the shaft outside of the upper housing. 45

11

31. The icemaker appliance of any one or more clauses herein, configured to execute the method of any one or more clauses herein.

This written description uses examples to disclose the invention, including the best mode, and also to enable any person skilled in the art to practice the invention, including making and using any devices or systems and performing any incorporated methods. The patentable scope of the invention is defined by the claims, and may include other examples that occur to those skilled in the art. Such other examples are intended to be within the scope of the claims if they include structural elements that do not differ from the literal language of the claims, or if they include equivalent structural elements with insubstantial differences from the literal languages of the claims.

What is claimed is:

1. An icemaker appliance, comprising:
  - a conduit fluidly coupling together a water reservoir, an icemaking vessel, and an ice reservoir; and
  - a pump configured to flow water through the conduit, wherein the icemaking vessel comprises an auger positioned at least partially within a cylinder, wherein a flowpath is formed between the cylinder and the auger, the auger forming an auger conduit extending in fluid communication from the flowpath to an outlet opening outside of the flowpath; and
  - a controller configured to selectively operate the pump and the icemaking vessel, the controller configured to: allow a temperature at the icemaking vessel to be above freezing temperature of water at the conduit; operate the pump to flow water through a closed loop circuit;
  - operate the pump to flow water through the closed loop circuit for a plurality of cycles through the closed loop circuit; and
  - operate the pump to flow water through the closed loop circuit for a plurality of cycles through the closed loop circuit until ice at the ice reservoir is removed.
2. The icemaker appliance of claim 1, wherein the auger comprises a shaft, the shaft forming a sidewall at which an inlet opening of the auger conduit is formed.
3. The icemaker appliance of claim 2, wherein the icemaking vessel forms an exit opening to an atmospheric pressure, the outlet opening positioned above the exit opening.
4. The icemaker appliance of claim 2, wherein the inlet opening is positioned in fluid communication with the flowpath.
5. The icemaker appliance of claim 1, wherein the conduit is formed in fluid communication with the flowpath at the icemaking vessel.

12

6. The icemaker appliance of claim 5, wherein the conduit is formed in fluid communication with the auger conduit.
7. The icemaker appliance of claim 1, wherein the ice-making vessel comprises an upper housing and a lower housing, and wherein the auger comprises a shaft, the shaft forming an upper portion extending through the upper housing, the shaft forming a lower portion extending through the lower housing.
8. The icemaker appliance of claim 7, wherein the auger conduit is formed extending substantially vertically through a main shaft body formed between the upper portion and the lower portion.
9. The icemaker appliance of claim 7, wherein the auger conduit extends through the upper portion, and wherein the outlet opening is positioned at the upper portion.
10. The icemaker appliance of claim 7, wherein the outlet opening is positioned at the upper portion of the shaft outside of the upper housing.
11. The icemaker appliance of claim 1, the controller configured to operate the pump to flow water through the closed loop circuit after the temperature at the icemaking vessel is above freezing temperature of water at the conduit.
12. The icemaker appliance of claim 1, the controller configured to:
  - drain the water through a drain plug after completing a plurality of cycles of flowing water though the closed loop circuit.
13. The icemaker appliance of claim 1, the controller configured to:
  - build a water height at the water reservoir to approximately an equal level to a height of the icemaking vessel.
14. The icemaker appliance of claim 13, the controller configured to:
  - egress water from the icemaking vessel to the ice reservoir via an upper exit at the icemaking vessel, the upper exit at an approximately equal height to the height of the icemaking vessel.
15. The icemaker appliance of claim 1, the controller configured to:
  - discontinue operation of a heat exchanger system to allow a temperature at the icemaking vessel to be above freezing temperature of water at the conduit;
  - drain the water through a drain plug after completing a plurality of cycles of flowing water though the closed loop circuit; then
  - restart operation of the heat exchanger system.
16. The icemaker appliance of claim 1, wherein the closed loop circuit comprises the auger conduit.
17. The icemaker appliance of claim 1, wherein the icemaker appliance is a nugget icemaking appliance.
